UNITED STATES PATENT OFFICE.

WILLIAM Y. DEAR, OF JERSEY CITY, NEW JERSEY, ASSIGNOR TO THE JERSEY CITY PRINTING COMPANY, OF JERSEY CITY, NEW JERSEY, A CORPORATION OF NEW JERSEY.

DESIGN FOR A DESK-PAD HOLDER.

43,497.

Specification for Design.

Patented Feb. 4, 1913.

Application filed October 21, 1911. Serial No. 656,008. Term of patent 14 years.

To all whom it may concern:

Be it known that I, WILLIAM Y. DEAR, a citizen of the United States, residing in the city of Jersey City, in the county of Hudson and State of New Jersey, have invented a new, original, and ornamental Design for Desk-Pad Holders, of which the following is a specification, reference being had to the accompanying drawing, forming part thereof.

The drawing is a perspective view of the desk pad holder showing my new design.

I claim:

The ornamental design for a desk pad holder as shown.

WILLIAM Y. DEAR.

Witnesses:

GERALD E. TERWILLIGER,
F. M. ARTLEY.
